United States Patent Office.

NATHAN F. MATHEWSON, OF BARRINGTON, ASSIGNOR TO HIMSELF AND
WILLIAM C. GREEN, OF PROVIDENCE, RHODE ISLAND.

Letters Patent No. 72,516, dated December 24, 1867.

IMPROVEMENT IN WINDOW-SASH LOCK.

The Schedule referred to in these Letters Patent and making part of the same.

TO ALL PERSONS TO WHOM THESE PRESENTS MAY COME:

Be it known that I, NATHAN F. MATHEWSON, of Barrington, of the county of Bristol, of the State of Rhode Island, have made a new and useful Invention having Reference to the Locking of Window-Sashes; and do hereby declare the same to be fully described in the following specification, and represented in the accompanying drawings, of which—

Figure 1 is a vertical section of a window-frame and its two sashes as provided with my invention.

Figure 2 is a horizontal section of the sash-lock.

Figure 3 is a rear-end view of it.

Figure 4 is a side view of the key.

In such drawings, A denotes the case for containing the operative parts of the lock, it being let into the outer face of the lower sash B. Within this case, and so as to turn horizontally on a centre, *c*, is a swing-bolt, C, provided with a toothed sector, D, which engages with a gear or pinion, E, arranged within the lock-case, and provided with a key-socket, *b*, to receive a key, formed as shown in fig. 4.

By inserting the key in the socket *b*, and revolving the pinion, the toothed sector and the swing-bolt may be moved so as to cause the bolt to protrude from the case, and enter a receiving-socket or recess, *c*, formed in the lower bar of the other sash G, or in a plate, *d*, fastened thereto. When the bolt is within the recess *c*, the two sashes will be locked together, so that neither can be moved vertically within the window-frame H. In order to hold the sector and bolt in position, when the latter is projected from the case, I employ a spring-dog or click, *g*, affixed at one end to the case, and having its other end bearing against the periphery of the sector; such dog being formed to enter between the teeth of the sector, and to be sprung therefrom by the pressure of the sector, caused by the key. In my arrangement of the locking-mechanism, it is wholly within the two sashes, instead of being in their upper edges, and in sight, as are most if not all other sash-fasteners, and there is a key-hole, *h*, to be made in the wood of the sash, in order to admit the key to the lock. My arrangement of the operative parts of the lock, with respect to the two next adjacent horizontal bars *i k* of the two sashes, is therefore productive of utility and advantage.

1. I claim the combination of the toothed sector and gear, provided with a key-socket, or its equivalent, with the radial swing-bolt, applied to a case, as specified.
2. I also claim the combination and arrangement of the spring-dog *g* with the radial swing-bolt, its toothed sector, and the operative gear thereof, as provided with a key-socket, or its equivalent, as set forth.
3. I also claim the arrangement of the radial spring-bolt, and its operative mechanism and receiving-socket, with the two bars *i k* of the two sashes, in manner as specified.

NATHAN F. MATHEWSON.
